UNITED STATES PATENT OFFICE.

THOMAS ELLIOTT JOHNSTON, OF AMITE, LOUISIANA, ASSIGNOR TO GULLETT GIN COMPANY, OF NEW ORLEANS, LOUISIANA, A CORPORATION OF LOUISIANA.

BOLL-BREAKER AND COTTON-CLEANER.

1,173,978.

Specification of Letters Patent. Patented Feb. 29, 1916.

Application filed November 13, 1915. Serial No. 61,372.

To all whom it may concern:

Be it known that I, THOMAS E. JOHNSTON, a citizen of the United States, residing at Amite, in the parish of Tangipahoa and State of Louisiana, have invented certain new and useful Improvements in Boll-Breakers and Cotton-Cleaners; and I do hereby declare the following to be a full, clear, and exact description of the invention, 10 such as will enable others skilled in the art to which it appertains to make and use the same.

This invention relates to breaks and gins, and more especially to gin feeders; and the 15 object of the same is to produce an improved machine for breaking the hulls and removing them along with the dirt, and then picking and feeding the cotton to the gin.

The present invention is an improvement 20 on my prior Patent No. 985,037 issued February 21, 1911, in which case the dirt and dust was taken from the cotton by pneumatic suction, but no provision was made for breaking the hulls. In other devices the 25 hulls have been broken and the cotton cleaned and picked, all while subjected to suction; but the purpose of the present invention is to clean the cotton and remove the hulls under suction, but to pick the cotton 30 under atmospheric pressure.

To this end the invention consists in the machine hereinafter more fully described and claimed, and as shown in the accompanying drawings wherein:

35 Figure 1 is a central vertical section of the machine, and Figs. 2 and 3 are front and rear elevations thereof. Fig. 4 is a perspective detail of the mechanism for setting the breaker board.

40 This entire machine is housed within a framework 1 having at one end an inlet 2 and opposite thereto an exhaust opening 3 communicating with a suction fan 4, while the numeral 5 designates the outlet for the cotton and 6 the outlet for the hulls and other dirt which is not drawn out the exhaust opening 3. Means not necessary to show are provided for carrying away the waste material, and the cotton outlet 5 will 45 also be connected with a gin by suitable means. Across the upper portion of the casing or framework is a trunk 7 carrying a screen 8 beneath which is an inlet passage 10 whose inner end is deflected and opens at 50 11 against the lower side of a boll crushing or

breaking roller 12. A curved screen 13 extends over this roller and separates it from the outlet portion of the trunk, which latter extends beneath the top of the casing to the exhaust opening 3, and the bottom 14 separates this portion of the trunk from the remainder of the mechanism. Underlying the breaking roller 12 is a slightly dished corrugated breaker board 15 yieldingly supported by springs 16 which rest on brackets 17 within the housing. At the ends of this board are pins 18 loosely engaging loops 19 in the arms of a yoke 20 which serves as a lever and is pivoted at 21 within the framework. A handle 22 is connected to the stem of the yoke and extends downward behind a spring 23 within a keeper 24, the inner edge of this handle having a rack 25 thrown normally into engagement with a tooth 26 by the spring as best seen in Fig. 1, and it follows 50 that by disengaging the rack from such tooth and adjusting the handle the lever or yoke 20 can be rocked on its pivots 21 so that its loops 19 depress the board 15 against the tension of the springs 16 to interrupt the breaking action which normally takes place by the ribs 27 on the roller 12 moving over the corrugations on the board 15. When the parts stand as seen in Fig. 1 the whole cotton passing inward along the passage 10 will 55 be directed between the roller and the board, and the bolls will be crushed, the fine leaf trash and particles of the boll lining being mostly drawn through the screen 13 by suction and carried out the opening 3.

Beyond and slightly below the boll breaking mechanism above described is a rotary valve designated as a whole by the numeral 30, the same acting also as a feeder which conveys the material forward to the picking mechanism described below. This valve comprises a number of blades 31 radiating from its shaft and each having a flexible tip 32 making close contact with the cylindrical casing 33 which has its inlet at 34 and its outlet at 35, and passage 10 is continued beyond the roller 12 in a passage 36 whose bottom 37 is fixed and stands adjacent the rear edge of the board 15 and whose top 38 converges toward the bottom and is shown in Fig. 1 as a separate member although it may be part of the element 14 above described. The passage 36 thus formed leads to the inlet 34 which communicates with the upper side of the casing 33, and the close fit of the 60 65 70 75 80 85 90 95 100 105 110

tips 32 in such casing prevents the suction device 4 from drawing air through this rotating member which therefore serves as a valve, while the movement of its blades in 5 the direction indicated by the arrow causes them to take up the material delivered from beneath the roller 12 and feed it downward through the outlet 35. The element 30 therefore serves as a valve to confine the suction 10 to the upper portion of the machine, and also as a feeder to carry the material forward and downward.

The retarding mechanism is situated just beneath the rotary valve where it acts on the 15 material passing through the outlet 35, and as shown it consists of two rolls 40' standing side by side and rotating toward each other as indicated by the arrows. The surface of each rolls is corrugated, and its ridges are 20 provided with radial pins 41', but the rolls are so situated that these pins are some little distance from each other on the contiguous or descending sides of the rolls as seen. It is important that these rolls rotate some- 25 what slowly as will be described below.

The picking mechanism stands in the lower part of the main framework and includes three similar rollers 40 each having radial pins 41 so disposed that they do not 30 lap each other on the contiguous sides of the rollers, and a scalloped screen 42 underlying these rollers and carried around the lowermost in what might be called a breast screen 35 which extends up to the point 44 where the retarding rolls deliver the material to the picking mechanism. The screen 42 has three scallops respectively underlying the three rollers shown, and these scallops are supported on cross bars 45 which stand above 40 a closed bottom 46 forming part of a framework which is hinged as at 47 within the main casing; said bottom being inclined toward the outlet 6 for the hulls and being movable to the position shown in dotted 45 lines in Fig. 1. The breast screen 43 stands slightly separated from the bottom 48 of the main casing at this point, which bottom inclines toward the outlet 6', and this section 50 of the bottom may be hinged or not as desired. I prefer to employ three rollers as shown, and they rotate in the same direction as shown by the arrows and at the same speed.

The driving mechanism is best seen in 55 Figs. 2 and 3. Power is led from a suitable source to the driving pulley 50 which is here shown as fast on the shaft 51 of the lowermost roller 40, and the shafts of the various rollers carry pulleys 52 which are 60 connected by belting 53 to cause them to move in unison as just stated. On the opposite end of the shaft 51 (see Fig. 3) is mounted a pulley 54 connected by a cross belt 55 with a somewhat smaller pulley 56 65 on the shaft 57 of the breaking roller 12,

whereby the latter is driven at a slightly higher speed than the rollers of the picking mechanism. The shaft 58 of the feeder or valve 30 is mounted at its extremities in bearings 59 carried by spiders 60 which are 70 detachably secured at 61 to the front and rear sides of the main casing, and one end of this shaft carries a removable sprocket wheel 62 over which passes a chain belt 63 as seen in Fig. 3. This belt leads around a 75 tightener 64 and a small driving sprocket 65 on the driving shaft 51, and it also leads in opposite directions around a pair of sprockets 66 fast on the shafts 67 of the rolls 40'. These sprockets are somewhat larger 80 than the driving sprocket, with the result that the rolls rotate more slowly than the driving shaft and therefore more slowly than any picker roller, and consequently they retard the feed of material to the picking 85 mechanism. The shafts 68 of the other picker rollers are mounted in bearings 69 as best seen in Fig. 3.

With this construction, the operation is as follows: The fan or suction device 4 having 90 been set in motion and power applied to the driving pulley 50, cotton is fed into the inlet 2 and along the passage 10 of the trunk 7, in which it is drawn gently upward toward the screen 8 and dirt and dust extracted from it through the screen and passed out the opening 3. With the parts standing as seen in Fig. 1, the cotton enters the breaking or crushing mechanism where the bolls are crushed between the roller 12 and the breaker board 15, and the fine leaf trash and particles of boll lining are mostly carried by suction through the screen 13 and out the opening 3. The crushed bolls are thrown by centrifugal action into the passage 36 and through the inlet 34 of the valve casing 33 into the feeder 30, whose blades not only pass the material onward but soon carry it out of position where the suction in 100 the upper part of the machine has any effect on it. For this reason the feeder serves as a rotary valve, and as soon as the tip 32 of its uppermost blade has passed the inlet opening 34 it is carried along under atmospheric pressure by the forward movement 105 of this blade. Delivered through the outlet 35, the material now falls into the retarding mechanism which consists of the rolls 40' rotating in the direction indicated, and by the tearing or reforming action of this mechanism much of the dirt and foreign matter is removed from the material and permitted to drop, while any lingering connection between the cotton and a particle of the boll is 110 here disrupted. The material next passes downward within the breast screen 43 and is acted upon by the fingers or pins of the lowermost picker roller; these carry it across the lowermost scallop of the screen 42 and on the ascending side of this roller deliver it 115 120 125 130

to the adjacent fingers 41 on the descending side of the next roller; and this operation is repeated between the second and third rollers, while the last roller tosses the cotton 5 out the outlet 5. Throughout this course the cotton has been whirled around the relatively large picker rollers and any remaining particles of boll or any dust or dirt therein has been allowed to fall through the 10 screen 42 onto the bottom 46 and out the outlet 6, because there is no suction within this portion of the casing. In other words, as soon as the material has passed into the feeder 30, it is free from the suction within 15 the trunk 7 and thereafter all action on the material takes place under ordinary atmospheric pressure.

The picking mechanism can be reached for cleaning or repair by swinging open the 20 bottom 46 on its hinge 47, and when the lowermost roller 40 is removed this gives access to the rolls of the retarding mechanism. The rotary valve or feeder can be reached by removing one of the spiders 60 and drawing 25 the shaft 58 out of the bearing in the other spider and taking the entire feeder out of the casing. The roller 12 may be reached by removing part of the top of the casing and lifting off the screen 13, and when this 30 roller is taken out the breaker board can be reached.

Whenever it is desired to clean cotton which may have already been removed from its bolls, the rack 25 of the handle is disengaged from the tooth 26 and the whole handle moved so as to swing the lever or yoke 20 and cause its loops 19 to bear downward on the pins 18 and thus depress the board 15. Hence this mechanism serves as a means 35 for adjusting the position of the board when desired, and as a means for practically throwing the breaking mechanism out of action when the board is adjusted to a considerable extent, though even then the ribs 40 27 will serve to feed the cotton in large or small lumps forward over the bottom 37 to the rotary valve 30.

What I claim is:

1. In a cotton boll breaker, the combination 50 with a casing, a chamber therein having one perforated wall subjected to suction, and a rotating ribbed breaker roller within said chamber; of a corrugated breaker board underlying and spaced from the roller, springs 55 pressing it normally upward toward said roller, pins in its extremities, a movable yoke whose arms have loops elongated in a direc-

tion parallel with that in which the board is moved by said springs, and manually operable means for adjusting the position of the 60 yoke whereby the engagement of the loops with the pins limits the movement of the board toward the roller but permits its movement away from the roller, for the 65 purpose set forth.

2. A boll breaker and cotton cleaner comprising a framework, a trunk across its upper portion having an inlet at one end and its other end connected with suction means, a screen in said trunk defining an inlet passage and extending over a roller chamber to which the passage leads, a rotating ribbed roller within said chamber, a corrugated breaker board yieldingly mounted beneath the roller, a circular casing having inlet and 70 outlet, imperforate walls connecting the outlet of the chamber with the inlet of the casing, a rotary valve within the casing, and cotton picking mechanism beneath the outlet of the casing.

3. In a boll breaker and cotton cleaner, the combination with a casing having a transverse cotton trunk with cotton inlet at one end and suction means at its other end, a screen within the trunk arched over a 85 chamber, and a ribbed breaking roller rotating within said chamber; of a corrugated breaker board underlying the roller, means for yieldingly supporting it, pins at its extremities, a pivoted yoke engaging said pins, 90 a handle for setting the yoke to move the board from the roller, means for holding the handle in adjusted position, cotton picking mechanism, and a rotary valve between said roller and mechanism and separating the 95 latter from the suction within the trunk.

4. In a boll breaker and cotton cleaner, the combination with a casing having a transverse trunk with cotton inlet at one end and a suction fan at its other end, a screen 100 within the trunk defining an inlet passage and arched over a chamber, and a ribbed breaking roller rotating within said chamber; of a corrugated breaker board underlying the roller, springs for yieldingly supporting it, pins at its extremities, a yoke having loops loosely engaging said pins, means for setting the yoke to move the board from the roller, cotton picking mechanism, and a rotary valve between said roller and 110 mechanism and separating the latter from the suction within the trunk.

. In testimony whereof I affix my signature.
THOMAS ELLIOTT JOHNSTON.
